PNEUMATIC TOOL

Jacob E. Feucht, Garfield Heights, Ohio, assignor to Westinghouse Air Brake Company, Wilmerding, Pa., a corporation of Pennsylvania

Filed Feb. 6, 1958, Ser. No. 713,694

5 Claims. (Cl. 121—32)

This invention relates generally to pneumatic tools, such as clay spades and the like, in which compressed air is fed into a cylinder in the machine housing to reciprocate a hammer. The hammer in turn strikes a tool which extends from the end of the machine. The air is then ported to the atmosphere.

Conventional tools of this general character have certain shortcomings, for example, foreign matter enters the chuck or tool end of the machine while the latter is operating to cause malfunctioning thereof. Another objection to these tools has been the discharge of air which heretofore was blown toward the operator or adjacent workmen, or was blown toward the side of the ditch being formed with a resulting spray of dirt over the area.

In operation these tools are held at their front end by the operator and in certain types of operations the tool becomes very hot and therefore difficult if not impossible to handle. This heat also adversely effects the wear life of certain parts.

A general object of the present invention is to provide a pneumatic tool which overcomes the above mentioned difficulties.

In accordance with the present invention a pneumatic machine has been provided in which the exhaust air is directed through the front end of the machine where it emerges at a reduced velocity and is directed toward the end of the tool. By so exhausting the air, dirt or other foreign matter is prevented from entering the working parts, such as between the tool shank and the chuck, while the machine is operating. Any foreign matter that has entered the machine during an idle period of the tool will be immediately ejected when the machine is started because of the large volume of air exhausted past these parts.

The invention also contemplates the cooling of the front end of the machine by the exhaust air so as to enable the operator to firmly grasp the machine at all times. This cooling is also effective to prevent overheating of the buffer parts and contributes to increased wear life thereof.

Another aspect of the invention provides a pneumatic machine having a front end construction which permits ready removal and insertion of the tools therein, and which permits the use of a relatively small diameter cylindrical shape, free of any projections, which can be conveniently held by the operator.

The invention furthermore provides a novel buffer construction and assembly for such a machine which will absorb the shock of the hammer impact on the tool when the tool is not in contact with the work, as when being withdrawn from the work.

These and other objects and advantages of the invention will appear hereinafter as this disclosure progresses, reference being had to the accompanying drawings in which:

Figure 1 is a longitudinal cross-sectional view of a machine made in accordance with the present invention; and

2

Figure 2 is a transverse cross-sectional view taken on line 2—2 of Figure 1, on an enlarged scale.

Referring more particularly to the drawings, the pneumatic machine shown for illustrative purposes is commonly referred to as a clay spade. The machine includes a generally cylindrical and elongated housing 10 having a backhead 11 rigidly secured thereto.

Compressed air is supplied to the machine via the connection 12 in the backhead and admission of this air is controlled by the actuating throttle valve 13. The valve in turn is controlled by the throttle lever 15, pivoted at 16, which shifts the link 17 to move the valve to the open position. A spring 18 urges the valve to the closed position.

Air is ported through passage 19 to chamber 20 in the valve chest 21 where it is diverted to either front chamber 22 via port 23, or to rear chamber 24 via port 25.

An annular groove or port 27 is formed in the bore 28 which forms chambers 22 and 24. Additional concentric bores 30, 31, 32 and 33 are formed in series along the length of the housing 10.

A hammer 35 is reciprocable in bore 30 and has a piston 36 formed integrally therewith which reciprocates within bore 28.

The piston and hammer are reciprocated in the conventional manner by alternately porting compressed air to the front and rear chambers 24 and 22 respectively, by the automatic operating valve 38. The compressed air that is used to reciprocate the piston is exhausted to atmosphere via annular groove 27 and passageway 40.

A chuck bushing 42 is mounted within bore 32 and the spade shank 43 has a collar 44 which engages the rounded end 45 of the bushing so as to be limited in its retraction within the housing. The hammer engages the inner end of the shank and the outer end extends outwardly of the housing and has a spade portion 46 formed thereon.

The bore 33 contains the split stop ring 48 against which the collar 44 strikes when moving in an outward direction. Another ring 49 is also secured in the bore and a resilient tubular-shaped buffer 50 is held captive in the bore between the rings 48 and 49.

The rings 48, 49 and the buffer are held in assembled relationship by the garter spring 51 which is snapped into its retainer groove 52.

The garter spring consists of a closely wound steel spring having coils with little space therebetween. The ends of the spring are joined to form a continuous ring which makes assembly and disassembly convenient, but a continuous ring is not essential.

When the spring is snapped into the groove 52, about one-half of its coils are exposed for holding ring 49. This provides a substantially complete circumferential bearing surface for positive retaining action against ring 49. The ring 49 not only provides a solid backing for the buffer 50 but also provides a good surface for action by the retaining spring.

The buffer serves to absorb the shock of the impact that occurs when the spade is struck by the hammer but is not in contact with the work. Such a situation occurs when the tool is being withdrawn from the work.

The spring snap ring, split ring and buffer assembly permits removal of these parts without the necessity for special tools. It is only necessary to insert a nail, screwdriver or other pointed object in either slot 53 behind the ring 51 in order to remove it.

The outside configuration of the end of the housing can be made relatively small and of smooth cylindrical shape which affords a surface that is easy to grip and hold for long periods of time.

The exhaust passageway 40 is in communication with bore 33 by means of the connecting port 54. The exhaust air passes outwardly through bore 33 and directly

past the buffer 50. This exhaust air not only prevents the ports from being overheated but also keeps foreign matter from accumulating in the housing. The air passes through areas of progressively larger cross section as it passes through to discharge and by the time it emerges from the machine, its velocity has been reduced considerably.

Another cross port 55 connects passage 40 with bore 31. Oil carried by the air will thereby reach the chuck 42 and its adjacent associated parts and thereby lubricate the same which facilitates the changing of the tools.

Various modes of carrying out the invention are contemplated as being within the scope of the following claims particularly pointing out and distinctly claiming the subject matter which is regarded as the invention.

I claim:

1. In a pneumatic machine having an axial bore therein and opening out one end thereof, a tool reciprocable in said bore within limits and extending freely through said bore and outwardly from said machine, an exhaust passageway extending substantially parallel to and laterally of said bore, said passageway being in air exhausting communication with said axial bore whereby exhaust air passes between said tool and said bore for blowing foreign matter generally axially from said machine, the air flow capacity of the space between the bore and the tool being greater than that of said passageway.

2. In a pneumatic machine having an axial bore therein and opening out one end thereof, a resilient buffer confined within said bore, means providing positive bearing stops at opposite ends of said buffer and preventing longitudinal displacement thereof, while permitting compression between said limit stops, a tool reciprocable in said bore and extending freely through said buffer and outwardly from said machine, an exhaust passageway in air exhausting communication with said axial bore whereby exhausted air is directed between said tool and said buffer for blowing foreign matter axially from said machine and for cooling said buffer.

3. In a pneumatic machine having an axial bore therein and opening out one end thereof, a pair of steel rings mounted in said bore, a tubular-shaped resilient buffer in said bore and between said rings, a retaining ring mounted in said bore for holding said rings and buffer captive in said bore, a tool reciprocable in said bore and extending freely through said buffer and outwardly from said machine, an exhaust passageway in air exhausting communication with said axial bore above said buffer where-

by exhausted air is directed between said tool and said buffer for blowing foreign matter axially from said machine and for cooling said buffer.

4. In a pneumatic machine having a hammer reciprocable in a housing by alternately porting compressed air to chambers on opposite sides of said hammer, said housing having an axial bore therein and opening out one end thereof, a resilient buffer securely mounted in said bore and retained against axial displacement therein, a reciprocable tool engageable by said hammer and extending freely through said buffer and outwardly from said housing, an exhaust passageway extending longitudinally of the housing outwardly of said bore and placing said chambers in air exhausting communication with said axial bore above said buffer whereby air exhausted from said chambers passes between said tool and said buffer for blowing foreign matter axially from said housing and cooling said buffer.

5. In a pneumatic machine having a hammer reciprocable in a housing by alternately porting compressed air to chambers on opposite sides of said hammer, said housing having an axial bore therein and opening out one end thereof, a pair of steel rings mounted in said bore, a tubular-shaped resilient buffer in said bore and between said rings, a retaining ring mounted in said bore for holding said rings and buffer captive in said bore, a reciprocable tool engageable by said hammer and extending freely through said buffer and outwardly from said housing, an exhaust passageway placing said chambers in air exhausting communication with said axial bore above said buffer whereby air exhausted from said chambers passes between said tool and said buffer for blowing foreign matter axially from said housing and cooling said buffer.
